UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,844, dated November 5, 1895.

Application filed October 3, 1895. Serial No. 564,552. Term of patent 3½ years.

to all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of rococo style of ornaments arranged in the form of panels, with sprays of flowers and leaves arranged in the center of said panels, as represented in the accompanying drawing. The border of the design is also formed of a series of connected rococo style of ornaments, forming connected panels, with sprays of flowers and leaves in the center of said panels, as shown in the drawing.

What I claim is—

1. The design for wall paper herein shown and described.
2. In the design for wall paper, the border herein shown and described.

Witness my hand this 27th day of September, 1895.

CHARLES BOOZ.
